UNITED STATES PATENT OFFICE.

LEVI W. YAGGY, OF LAKE FOREST, ILLINOIS.

ADVERTISING APPARATUS.

SPECIFICATION forming part of Letters Patent No. 620,689, dated March 7, 1899.

Application filed May 6, 1897. Serial No. 635,357. (No model.)

To all whom it may concern:

Be it known that I, LEVI W. YAGGY, a citizen of the United States, residing at Lake Forest, in the county of Lake and State of Illinois, have invented a certain new and useful Improvement in Advertising Systems and Apparatus, which is fully set forth in the following specification, reference being had to the accompanying drawings, in which—

- 10 Figure 1 is an elevation of the casing, showing the location of the different apertures. Fig. 2 is a section of the mechanism, on an enlarged scale, on the line 2 2 of Fig. 1. Fig. 3 is a rear elevation of the indicator operating 15 and controlling mechanisms with their rear plates removed and some parts broken away to more clearly disclose the structure and operation of the parts. Fig. 4 is a plan view of the same mechanism on the plane indicated 20 by the line 4 4 of Fig. 3. Fig. 5 is an enlarged elevation, partly in section, showing some of the details of construction of the indicator-shifting mechanism, on the line 5 5 of Fig. 4. Fig. 6 is a side elevation, on the same scale, of 25 the mechanism shown in Fig. 5, on the line 6 6 of Fig. 3. Fig. 7 is a side elevation showing the train of reducing-gears and the detent-releasing mechanism therefor. Fig. 7^a is a detached view of the crank-shaft operating 30 the indicator-shifting mechanism. Fig. 8 is an elevation of a portion of three of the indicating-dials, showing how the combinations are effected. Figs. 9, 10, and 11 are elevations showing portions of the different indicating-dials. Fig. 12 is an elevation of a portion of the advertising display-dial. Fig. 13 shows sectional details of the clamps employed in securing the dials to their shafts.

My invention relates to a new and useful 40 system for displaying advertising matter and attracting attention thereto and to mechanism for operating such a system.

In carrying out my invention I provide a plurality of display devices or indicators, 45 which may consist of dials or wheels or some similar mechanism, and upon these indicators I place a portion or portions of the indication or indications, so that it takes the combined indicators to display a complete indication. I place upon these individual indicators a plurality of indications, so that combinations of these partial indications may be

effected to get several different complete indications. If two indicators are employed, each giving two half-indications, by combining the two half-indications four different complete indications could be obtained. If three indicators are employed, each giving three one-third indications, by combining the three one-third indications twenty-seven different complete indications can be obtained. In connection with these changeable indications I employ advertising matter so located as to necessarily attract the observer's attention while he is looking at the indications or 60 waiting for a new combination to be formed. I may make said advertising matter also changeable, so as to employ a plurality of advertising display indications.

My invention further relates to a novel mechanical movement and to novel detent mechanism therefor.

As a housing for the indicators and their operating mechanism I employ a casing A of any shape or construction required to accommodate said indicators and mechanism. As shown in Fig. 1, I employ a plurality of apertures in said casing, through which apertures the desired portion or portions of the indication or indications appear. The aperture B 80 is employed to disclose such portions of the three indicating-dials C, C', and C², which are employed to display the matter which is intended to amuse or attract the attention of the observer to the device. In proximity to this 85 aperture B are other apertures B', through which it is intended to display advertising matter so that the observer while watching the display in the aperture B will be compelled to notice the advertising matter displayed in the apertures B'.

Referring especially to Figs. 8 to 11, it will be seen that I employ a series of three concentric dials C, C', and C², these dials differing in size and only a portion of their faces 95 being employed for indicating purposes. In the devices shown I have divided the indicating portion of each dial into six sectors of equal size, and each sector is decorated with different kinds of the same portion of the 100 whole design. As will be seen from Fig. 8, the smaller dial contains illustrations of the chin and mouth of individuals of widely-differing appearances, any one of which chins

and mouths is arranged to register accurately with the features on the middle dial C', which contains the middle portion of the face, including the eyes, ears, nose, &c., of the same individuals, while the indicating portion of the largest one, C², of this set of dials contains the forehead, &c., of these different individuals. It will readily be seen that if the position of these dials is shifted so as to make different combinations of the different portions of the faces grotesque and ludicrous results will be obtained and that such indications and changes will furnish a source of amusement and entertainment to the average spectator. It will be understood that these changes of the dials to produce the different combinations might be effected manually or in any other way desired; but I prefer to effect them automatically by means of some form of motor mechanism. I will now describe the form of mechanism which I have devised for this purpose and which I at present consider best adapted for such purpose.

As will be best seen from Fig. 2, each of the dials is connected to one of a series of concentric shafts or sleeves D, D', D², and D³. The dial C is connected to its shaft D by means of two circular plates c and d, between which it is clamped and which are secured to said shaft by a screw, as clearly shown in Fig. 2. To insure the dials against shifting their position relatively to the shaft to which they are connected, these plates are provided with spurs, as seen in Fig. 13, which take into the body of the dial. The dial C' is secured to a sleeve D', which is rotatably mounted on the shaft D. Instead of employing the form of plates c and d employed in connection with the dial C and the shaft D, I may employ, in connection with the dials C', C², and C³ and the sleeves D', D², and D³, the disks c', c², and c³, which may be integral with or otherwise firmly fastened to the ends of the sleeves D', D², and D³, and coöperating against these disks c', c², and c³ I employ the disks d', d², and d³, constructed, as shown in Fig. 13, with an interiorly-screw-threaded body and projections on the face of the disk proper. As the ends of the sleeves D', D², and D³ next to the disks c', c², and c³ are screw-threaded, it will be seen that in order to secure the dials firmly in position it is only necessary to place them between the disks c', c², and c³ and the disks d', d², and d³ and screw the last-mentioned disks firmly against the first-mentioned disks. Rigidly fastened to the opposite ends of the shaft D and sleeves D', D², and D³ are the disks E, E', E², and E³. These disks have their peripheries notched, as best shown in Fig. 5, where it will be seen that every alternate notch e is square and coöperates with the detents or pawls G, G', G², and G³, while the remaining notches e' are rounded, but have approximately square shoulders on one side, which coöperate with the operating-dogs F, F', F², and F³. These operating-dogs for the general purposes of the invention might be of

any desired shape and construction; but I have shown them as constructed of long wires, consisting of the principal horizontal body portion f, the short vertical portion f', the relatively short horizontal portion f², the vertical portions f³, the under horizontal portions f⁴, and the hooked portions f⁵. These long horizontal portions f serve merely as a connecting medium between the portions that coöperate with the disks E, E', E², and E³ and the actuating mechanism for said dogs or pawls F, which will be described later on.

It may be stated at present that at each movement of the mechanism the operating-pawls F are reciprocated in the direction of their length, and it will be seen from Figs. 3 and 4 that when the dog F is drawn to the right its hook f⁵ will take against the shoulder of the notch e' adjacent to it and that the movement of the dog will carry the disk E forward a distance equal to the distance between two of said notches e'. As the dog F returns to the left this disk E will not be affected by its movement, but will remain in its advanced position. The detents G, G', G², and G³ are pivotally mounted upon a horizontal rod g, and their free ends are normally held against the peripheries of the disks E, E', E², and E³ by means of the small springs g' employed for that purpose. The lower ends of these detents G, G', G², and G³ are bent at a right angle, so as to form lugs g². (Best shown in Figs. 5 and 6.) These lugs g² take into the square notches e and normally hold the wheels E from movement in either direction. These detents G, G', G², and G³ have other lugs g³ projecting inwardly, as shown in Figs. 5 and 6, with which oppositely-projecting lugs f⁶, located upon the vertical portions f' of the operating-dogs F, F', F², and F³, contact.

It will be seen from an inspection of Figs. 3, 4, 5, and 6 that as the operating-dogs F, F', F², and F³ move to the right at the beginning of their movement their lugs f⁶ contact with the lugs g³ of the detents G, G', G², and G³ and swing said detents so that their lugs g² pass out of the notches e and release the disks E, E', E², and E³, so that the further movement of the pawls F, F', F², and F³ may carry the disks with them until the end of their stroke, when the lugs g² of the detents G, G', G², and G³ will take into the next notches e of the disks E, E', E², and E³ and lock them in their advanced position.

A construction such as hitherto described would cause all of the disks E, E', E², and E³ to be operated by their pawls F, F', F², and F³ every time that said pawls were reciprocated, if said pawls were reciprocated simultaneously. If these pawls were to be operated manually, there would be no need for operating them simultaneously, but as it is desired to operate them simultaneously by the motor mechanism some means must be provided whereby they will not all operate their disks E, E', E², and E³ simultaneously; otherwise the different combinations would

not be made, but the same portions of the same faces would always appear together and there would be no changes. In order to effect these varying movements of the disks E, 5 E', E², and E³, the following mechanism is employed:

What may be termed an "eccentric" shaft H is journaled in the framework immediately under and at right angles to the portions f² 10 of the dogs or pawls F, F', F², and F³, and has rigidly attached to one end thereof the gearing pinion H'. This shaft H has three bearing-surfaces h, h', and h², arranged to co-operate with the portions f² of the pawls or 15 dogs F, F', and F², respectively. These portions are arranged at such a distance and in such directions from the axis of the shaft H that when one of said portions—say h—is in its lowermost position, as indicated in Fig. 20 3, the other two portions h' and h² will be in a position or planes above the axis of the shaft H. In case this eccentric shaft H is to be employed to control three dogs or pawls, as in the construction illustrated, the arrangement of the shaft is substantially as 25 follows: The ends of the shaft of course are mounted in concentric bearings, while the three bearing-surfaces h, h', and h² are arranged at a certain distance from the axis of the 30 shaft and at an angular distance of one hundred and twenty degrees from each other. The connecting portions between the two outer bearing-surfaces and the adjacent ends, respectively, of the inner bearing-surface 35 are in a straight line, and the complete construction is such as is clearly shown in Figs. 2, 3, 4, and 6. It results from this construction that when the shaft H is in this position the operating-dog F will have its hook f³ in the plane of the uppermost teeth or 40 notches e' of the disk E, so that the reciprocation of said dog F will actuate said disk E. While the shaft H is in this position, its portions h' and h², which co-operate with the 45 dogs F' and F², are above the axis of the shaft and hold said dogs up out of the plane of the teeth or notches e' of their respective disks E' and E², so that the reciprocation of these dogs F' and F² will not operate their 50 disks E' and E². Moreover, it will be seen that the lugs f⁶ on the dogs F' and F² will be raised above the plane of the lugs g³ on the detents G' and G², so that said disks E' and E² will not be released and cannot be accidentally moved forward. In their lower or 55 operative position the dogs F, F', &c., are in a plane substantially tangent to the disks E, E', &c., while in their upper or non-operative position the plane which they occupy 60 is not tangent to these disks. Incidentally it may be stated that this construction of the detents, positively locking their disks from rotation in either direction, except when they are to be operated by the movement of 65 the operating-dogs, is a great advantage, as it absolutely prevents any accidental movement or displacement of the disks, and, more-

over, enables me to dispense with the fixed washers, which are customarily placed between the adjacent disks of registering or 70 other mechanisms of this class, as the fact that each wheel is positively locked, except when it is to be operated, prevents any wheel being moved forward accidentally by the friction resulting from the movement of its 75 adjoining disks. It will be seen from this construction that so long as the shaft H remains in the position shown the disk E will be moved forward one space every time the dogs F, F', F², and F³ are reciprocated. When it 80 is desired to cease moving the disk E and to move either of the disks E' or E², it will be necessary to turn the shaft H until the portion h' or h² corresponding to the disks desired to be operated is placed in its lowermost position 85 beneath the axis of the shaft.

By an inspection of the disks E, E', and E², as shown in Fig. 3, it will be seen that they have six notches or teeth e', so that each movement of the disk moves another section of the 90 indication upon the dials C, C', and C² into view at the aperture B. In the construction that I have shown the largest or advertising dial C³ is divided into ten sections, and accordingly its disk E³, as seen in Fig. 5, has ten 95 teeth or notches e'. The operating-dog F³, co-operating with this disk E³, has no portion f² and is so arranged as not to be affected by the position of the shaft H, and consequently the advertising-dial is shifted at each movement of the dogs F, F', F², and F³. As this advertising-dial disk E³ moves continuously, or, rather, is actuated at regular intervals, so long as the device is in operation, I employ 100 said disk E³ to shift the position of the shaft H. To effect this result, I journal on the side of the casing, in the same plane as the gear-pinion H', a gear-wheel J of twice the diameter of and meshing with the gear-pinion H'. On the surface of said gear-wheel J, I place 110 a number of equidistantly-disposed pins J', which are in the plane of and contacted by the laterally and outwardly projecting spurs e², equidistantly disposed upon the face of the disk E³, as shown in Figs. 5 and 6. A bell-crank-shaped dog J² is pivotally mounted beneath the wheel J and in the plane of the pins J' and has upon one arm thereof two shoulders J³, which are so arranged as to securely hold the wheel J in its position by reason of 120 the co-operation of said shoulders with the pins J'. A pin e³, projecting from the spur e² into the plane of the other arm of the dog J², takes against said dog and moves it sufficiently to unlock the wheel J from the dog J² just before the spurs e² contact with the pins J' to advance the wheel J one space every time one of 125 said spurs e² passes said wheel. The dog J² is spring-pressed or held by gravity so as to normally lock the wheel J from movement. In 130 the construction I have illustrated the disk E³ is provided with two of the spurs e³, and consequently at every fifth actuation of the disk E³ the wheel J is moved forward through

a radial distance of sixty degrees, and consequently moves the pinion H' and the shaft H through a radial distance of one hundred and twenty degrees, thus bringing another one of the surfaces or portions h , h' , and h^2 into its lowest position, so as to bring another one of the disks E , E' , and E^2 into operation. As these disks E , E' , and E^2 have six teeth each, it will be seen that one disk is moved forward five spaces and then remains stationary, while the remaining disks move through five spaces each at separate intervals, when the first disk will again come into action. By this construction it will be seen that every one of the possible two hundred and sixteen combinations will be effected automatically. From a consideration of the movement of these disks it will be seen that it is regular and in succession and *seriatim*. The first disk moves one space at a time through five spaces, when it stops movement, and the second disk moves a space at a time through five spaces, when it stops movement, and the third disk moves through a space at a time through five spaces, when it stops movement and the first disk begins movement again, and, moving through a space at a time, moves five spaces, and so on throughout a continuous cycle.

The mechanism for reciprocating the operating-dogs F , F' , F^2 , and F^3 will next be considered, reference being had especially to Figs. 2, 3, 4, and 7. The power is applied to the motor mechanism by means of a crank-handle K , which is applied to a winding-armor K' , which is journaled in the back of the casing and has on its inner end a gear-pinion K^2 , rigidly fastened thereto. This pinion K^2 meshes with an internally-toothed gear L , cut in a flange L' , arranged on the periphery of a disk L^2 , which is rigid with a sleeve L^3 , which may be journaled upon the shaft M , arranged in said casing. A strong spiral spring N is fastened to the sleeve L^3 at one end and at the other end to the inner periphery of the spring-barrel N' , which may be mounted upon the shaft M directly or by means of a sleeve. A dog O , fastened to the casing, engages with the gear-teeth L and prevents any backward movement of the disk L^2 and the sleeve L^3 . If the spring-barrel N' be held by any means, it will be seen that as the handle K is turned to the right the spring N will be wound up and put under tension. This spring-barrel N' has a gear N^2 upon its outer periphery, and this gear N^2 meshes with a train of suitable gearing P , which terminates in a screw Q , which has a small fan-wheel Q' upon its shaft.

It will be seen from an examination of the gearing as shown in Fig. 3 that if no intervening mechanism is employed the spring N will move the train of gearing at a rate proportional to its internal resistance and the resistance of the fan-wheel Q' . At a suitable position in this train of gearing I place a shaft R , which is of the form and construction best shown in Fig. 7^a, being what is generally

known as a "double-crank" shaft. This shaft has two oppositely-disposed eccentric portions R' and R^2 , and upon the longer eccentric portion R' are mounted the bearings for the dogs F , F' , and F^2 , while upon the oppositely-disposed shorter eccentric portion R^2 is mounted a bearing for the dog F^3 . It results from the construction of this eccentric shaft and the arrangement of the bearings of the dogs F , F' , F^2 , and F^3 thereupon that during one-half of the revolution of said shaft R the disk E^3 will be moved forward, while during the other one-half of the movement of said shaft one of the disks E , E' , and E^2 , depending upon the position of the shaft H , will be moved forward. The resulting alternate movement of the dial C^3 and the dials C , C' , and C^2 prevents any possible disarrangement of the parts and failure to operate, which might occur if the disks E^3 and disks E , E' , and E^2 should move simultaneously instead of alternately.

The construction so far employed would cause the advertising-dial C^3 and the indicating-dials C , C' , and C^2 to be moved along in quick succession, whereas it is desirable to have each indication remain in view for a sufficient period of time, so that the observer will have considered the amusements indication thoroughly and will allow his attention to be drawn to the advertising exhibit or display. To effect this intermittent movement of the mechanism, I employ an ordinary time-movement S , which is conveniently mounted above the casing which contains the motor mechanism and has upon one of the wheels of its train one or more lugs S' , which at every revolution of said wheel will contact with the end of a lever T , which is pivoted at a point T' to the casing or some other stationary portion of the mechanism. The lower end of the lever T is formed in a loop or hook T^2 , which surrounds a somewhat similar lever U , which is similarly pivoted or fulcrumed at U' . The lower end of this lever U terminates in an arm U^2 , which extends into the plane of and in front of an arm Q^2 , fastened to the screw-shaft Q . The upper end of this lever U terminates in an arm or hook U^3 , which projects into the plane of a notched disk V , connected to the train of gearing P . This notched disk V has one or more equidistantly-disposed notches V' , into which the arm U^3 of the lever U normally takes. When the lever U is in the position shown in Fig. 3, it will be seen that the arm U^3 , having taken into the notch V' , will prevent the movement of the train of gearing P and that the movement of said train of gearing will be further prevented by reason of the arm Q^2 on the shaft Q contacting with the arm U^2 on the lever U . When the time-movement S is moved forward a sufficient distance to bring the pin S' into contact with the upper end of the lever T , the movement of said lever by reason of its hook T^2 will swing the lower end of the lever U to the right until the arms U^2 and Q^2

are disengaged and the arm U^3 is removed from the notch V' . The motor is now free to run and will run, the arm U^3 riding on the outer surface of the notched disk V , thus preventing the arm U^2 from getting into the plane of the arm Q^2 until the next notch V' in the notched disk V comes around and receives the arm U^3 , when the arm U^2 of the lever U will move into the plane of the arm Q^2 .

10 on the shaft Q and stop the motor-train. During this movement the shaft R will have been moved one-half a rotation and the operating-dogs $F F'$ reciprocated to shift the indicating or advertising dial, as the case may be.

15 It will be seen that my invention is a generic one and that the apparatus employed is capable of many modifications, and I do not desire to be limited except as required by the state of the art and as suggested by the terms 20 of the claims.

I claim—

25 1. In an indicating system, the combination of a plurality of indicating members each carrying a plurality of fractional indications, so that the system is capable of a plurality of combinations, with automatic mechanism for shifting said members separately and *seriatim* so as to vary the combinations.

30 2. In an indicating system, the combination 30 of a plurality of dials, each dial carrying in its different sectors a plurality of fractional indications, so that the system is capable of a plurality of combinations, with automatic mechanism for shifting said dials separately and *seriatim* so as to vary the combinations formed by the fractional indications of the different sectors.

35 3. In an advertising system, the combination 40 of a plurality of indicating members each carrying a plurality of fractional indications, so that the system is capable of a plurality of combinations, with automatic mechanism for shifting said members separately and *seriatim* so as to vary the combinations, and

45 advertising matter located in proximity to the said indicating members, substantially as and for the purpose described.

4. In an advertising system, the combination 50 of a plurality of indicating-dials each carrying a plurality of fractional indications, so that the system is capable of a plurality of combinations, with a dial containing advertising matter located in proximity to the indicating-dials, and automatic mechanism for shifting said advertising-dial at regular intervals and said indicating-dials separately and *seriatim* at said intervals so as to vary the combinations, substantially as and for the purpose described.

55 5. In an indicating system, the combination 60 of a plurality of indicating members each carrying a plurality of fractional indications, so that the system is capable of a plurality of combinations, with motor mechanism for automatically shifting said members separately and *seriatim* at regular intervals of time so as to vary the combinations.

6. In an indicating system, the combination of a plurality of indicating-dials, each carrying a plurality of fractional indications, so 70 that the system is capable of a plurality of combinations, with motor mechanism for automatically shifting said dials separately and *seriatim* at regular intervals of time to vary the combinations, and a casing with an aperture to determine what portions of the dials shall be exposed.

7. In an indicating system, the combination of a plurality of indicating members each carrying a series of indications and movable relative to each other through a cycle to display successively all of the indications, with mechanism coöperating with said indicating members for moving one of them a portion of its cycle, then moving another member for a portion of its cycle while the previously-operated one remains unmoved, substantially as and for the purpose described.

8. In an indicating mechanism, the combination of a plurality of movable indicating 90 members, with another movable indicating member, mechanism for moving said last-mentioned member and any one of said first-mentioned members at regular intervals, and connections controlled by said last-mentioned 95 member and coöperating with the mechanism for moving the first-mentioned members, whereby the first-mentioned members will be moved alternately, substantially as and for the purpose described.

100 9. In an advertising device, the combination of a series of movable indicating members bearing matter adapted to attract attention and capable of different combinations, with a movable advertising member, and motor mechanism for moving one of said indicating members and the advertising member, capable of automatically varying the combinations of the indicating members through all possible combinations, substantially as described.

105 10. In an indicating mechanism, the combination of a plurality of indicating members, with another movable indicating member, mechanism for moving said last-mentioned 115 member and any one of said first-mentioned members alternately at regular intervals, and connections controlled by said last-mentioned member and coöperating with the mechanism for moving the first-mentioned members, 120 whereby the first-mentioned members will be moved alternately.

11. In an indicator-operating mechanism, the combination of the rotatable disks, with the reciprocating dogs for operating said 125 disks, and mechanism for alternately throwing the dogs coöperating with some of said disks into and out of operation comprising connections with one of said disks which is always operated thereby while the machine is 130 in operation, substantially as and for the purpose described.

12. In an indicator-operating mechanism, the combination of the disks, with the recip-

rocating dogs for operating said disks, automatic mechanism for alternately throwing some of said dogs into and out of the plane tangent to the disks, comprising connections 5 with one of said disks operated thereby, the dog of which is not thrown out, and mechanism for reciprocating said dogs, substantially as and for the purpose described.

13. In an indicator-operating mechanism, 10 the combination of the disks, with the reciprocating dogs for operating said disks, mechanism for reciprocating said dogs simultaneously, and controlling means operated by one of said disks for determining which of the 15 other disks shall be operated.

14. In a train of gearing, the combination 20 of the lug Q^2 , with the detent-lever U, the notched disk V, the lever T, and the time-train having the lug S' to contact with the lever T, all coöperating substantially as and for the purpose described.

15. In an advertising apparatus, the combination of the arbor K' carrying the gear-pinion K^2 , with the disk L^2 having the gear L, 25 the dog O coöperating with the gear L, the spring-barrel N' containing the spring N fastened thereto and to the disk L^2 , a plurality of indicating members capable of forming different combinations, and mechanism between 30 said indicating members and the spring-barrel N' for automatically varying said combinations, all coöperating substantially as and for the purpose described.

16. In an advertising device, the combination 35 of the toothed disks, connected to or carrying display matter, with the reciprocating dogs for advancing said disks, and the crank-shaft upon which said dogs are mounted at different angles so that the operative movement of said dogs shall be at different times, 40 substantially as and for the purpose described.

17. The combination of the toothed disks, 45 with the reciprocating dogs for advancing said disks, the crank-shaft upon which said dogs are mounted, one of said dogs being mounted at a different angle from the remain-

ing dogs so that the operative movement of the said dog shall be at a different time from that of the remaining dogs, and a controlling 50 mechanism operated by the movement of said single dog for determining which of the remaining dogs shall operate its disk during its reciprocation.

18. In a train of gearing, the combination 55 of the shaft Q carrying the lug Q^2 , with the centrally-pivoted lever U carrying the arms U^2 and U^3 , the notched disk V, the lever T operatively connected with the lever U, and the time-train having the lug S' to contact 60 with the lever T, all coöperating substantially as and for the purpose specified.

19. The combination of a plurality of disks, 65 with reciprocating dogs therefor, detents co-operating with said disks to positively lock them from movement in either direction, and moved out of locking engagement by the initial movement of said pawls, and means for determining which of said pawls shall move in the plane tangent to its disk and detent, 70 substantially as and for the purposes described.

20. The combination of the disks having the notches e and e' , with the dogs having the hooked portions f^5 , the lugs f^6 and the horizontal portions f^2 , the detents having the noses g^2 and the lugs g^3 , and the shaft H having the eccentric portions h , h' , and h^2 , all co-operating substantially as and for the purpose 75 described.

21. The combination of the disks having the notches e and e' , with the dogs having the hooked portions f^5 , the lugs f^6 , and the horizontal portions f^2 , the detents having the notches g^2 and the lugs g^3 , the shaft H having 85 the eccentric portions h , h' , and h^2 , and the pinion H' , the wheel J meshing with said pinion H' , and means for operating said wheel J at intervals, substantially as and for the purposes described.

LEVI W. YAGGY.
